(57) **CLAIM**

The ornamental design for a multi-use cover, as shown and described.

DESCRIPTION

FIG. 1 is a perspective view of a multi-use cover showing my new, original, and ornamental design when covering an infant carrier;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front view of the multi-use cover, shown worn by a user in a first nursing configuration;

FIG. 9 is a rear view thereof;

FIG. 10 is a right-side view thereof;

FIG. 11 is a left-side view thereof;

FIG. 12 is a front view of the multi-use cover, shown worn by a user in a second nursing configuration;

FIG. 13 is a rear view thereof;

FIG. 14 is a front view of the multi-use cover, shown worn by a user in a third nursing configuration;

FIG. 15 is a rear view thereof;

FIG. 16 is a front view of the multi-use cover, shown worn by a user in a fourth nursing configuration;

FIG. 17 is a rear view thereof;

FIG. 18 is a front view of the multi-use cover, shown worn by a user in a first scarf configuration; and,

FIG. 19 is a front view of the multi-use cover, shown worn by a user in a second scarf configuration.

The broken lines shown within the multi-use cover depict portions of the article that form no part of the claimed design. The broken lines that show the baby carrier in FIGS. 1-7 and mannequin in FIGS. 8-19 form no part of the claimed design.

1 Claim, 18 Drawing Sheets
